UNITED STATES PATENT OFFICE

JOSEPH FRED ROBBIN, OF GRAND RAPIDS, MICHIGAN

OAR

Application filed March 23, 1931. Serial No. 524,565.

The present invention relates to oars for propelling boats; and its general objects are: to provide an improved "bow-facing" oar; to provide an oar which may be used in the usual manner and also as a bow-facing oar; to provide such an oar which may be turned about its longitudinal axis in rowing; to provide such an oar which may be readily and securely mounted on, and removed from, the boat; and more particularly, to provide such an oar having improved mountings therefor, improved constructional features and improved parts and mechanisms and combinations thereof whereby said general objects are attained.

These and any other and more specific objects hereinafter appearing are attained by, and the invention finds preferable embodiment in, the structures particularly described in the body of this specification and illustrated by the accompanying drawings, in which:

Figure 1 is a top plan view of the middle parts of a bow-facing oar;

Figure 2 is a vertical sectional view thereof and of a side of the boat on which the oar is mounted, taken on line 2—2 of Figures 1 and 3;

Figure 3 is a vertical sectional view of the same taken on line 3—3 of Figure 2;

Figure 4 is a top plan view of the middle parts of the oar, showing one position of the same in solid lines and another position thereof in dotted lines;

Figure 5 is a transverse sectional view, taken on a vertical plane corresponding to line 2—2 of Figure 3, of middle parts of the oar and a side of the boat on which the oar is reversely mounted in a position to be operable in the usual manner, i. e. by a rower facing toward the stern of the boat;

Figure 6 is a top plan view of a boat and a pair of oars mounted in bow-facing operation thereon;

Figure 7 is a vertical sectional view of certain parts shown in Figure 5, taken on line 7—7 of that view;

Figure 8 is a top plan view of middle parts of the oar, and of a side of the boat, showing a modified construction of the oar;

Figure 9 is a vertical sectional view thereof and of a side of the boat, taken on line 9—9 of Figure 8; and

Figure 10 is a vertical sectional view of the same taken on line 10—10 of Figure 9.

The oar illustrated by these drawings is of the "bow-facing" type, i. e. it is adapted to be operated by a rower facing the bow of the boat. The said oar comprises the blade portion 1 and the handle portion 2, these portions being mounted swingably horizontally by pivot pins 3, 4, on a member, designated generally 5, and comprising upper and lower horizontally disposed plates 6, 7 spaced to receive said portions of the oar between them, and connected together by posts 8.

The adjacent ends of said portions 1, 2 of the oar are connected swingably horizontally by a pivot pin 9 passing through the end portions of reinforcing bars 10, 11 on oar portion 1 and 12, 13 on the portion 2 of the oar, said bars being secured by bolts 14, 15 passing therethrough and through said oar portions respectively. The plates 6, 7 have slots 16, 17 therethrough, the pivot pin 4 of oar member 2 extending through the same and being movable laterally therein to permit the relative swinging movement of the oar portions, this pivot pin having at its ends disks 18 bearing on the outer surface of said plates in such movement.

To the plate 7 is united, as by spot welding indicated at 19, a yoke 20 having downwardly extending ears 21 bored at 22 to receive the pintles 23 extending in the boat's longitudinal direction and carried by the post portions 24 of a mounting member 25 secured as by screws 26 on the upper edge of the boat's gunwale 27.

The oar's blades 1 are raised and lowered by the turning movement of the yoke 20 on the pintles 23. The oar is removably mounted on the boat by moving this yoke 20 toward the right hand side of Figure 3, the free ends of the pintles 23 thus entering the bores 22, whereupon the oar is held in this mounted position, as particularly well seen in Figure 3, by the catch bar 28 carried on the yoke by the screw 29 passing loosely through said bar. When it is desired to remove the oar, the free

end 30 of this bar is moved upwardly against the pressure of a spring 31 far enough to pass above the upper end of the post 24.

The oar is shown in Figures 1, 2, 3, 4 and 6 5 so mounted on the boat's gunwale as to be operated by a rower facing the bow 32 of the boat 33 and seated on the thwart 36. But, if it be desired to operate the oar in the usual manner, i. e. by a rower facing the stern 35 10 of the boat and sitting on the thwart 34, the oar, the plates 6, 7, yoke 20 and parts carried thereby are removed from the pintles 23 and turned half-way about the oar's longitudinal axis, and the upstanding parallel arms 37 of 15 a locking element 38 are inserted through the openings 39 in the plate 6 and in straddling relation with the bars 10, 11, to hold the oar's two portions 1, 2 against relative movement, as shown in Figure 5.

20 This locking element's portion 60 is turnably mounted on a spindle 40 thrust into a vertical rotary bearing 41 in a post member 42 secured as by screws 43 to the boat's gunwale as seen in Figure 5. In this operation 25 of the oar by a rower facing rearwardly, the two portions 1, 2 of the oar are thus locked together and the entire oar swings about the axis of the spindle 40 as in a rowlock of usual form. The spindle 40 has a rounded head 61 30 on which the plate 6 bears so that the blades 1 may be raised and lowered.

In the modified construction shown in Figures 7, 8 and 9, the bow-facing oar has blade and handle portions 1¹ and 2¹ carried swingably horizontally by the member 5¹ comprising parallel plates 6¹, 7¹, and operates as does the oar shown in Figures 1, 2, etc. But in this modified construction the ends of the bars 10¹, 11¹ are connected to the ends of the 40 bars 12¹, 13¹ by a Hooke's joint (or other similarly acting joint) comprising the part 50 whose aligned spindles 51 turn in bearings 52 in bars 10¹, 11¹, and whose spindles 53 (at right angles to spindles 51) turn in bearings 54 in bars 12¹, 13¹, these bars being mounted 45 on the oar portions 1¹, 2¹ by bolts 14¹, 15¹ respectively. A sleeve 55 in which the oar portion 1 bears turnably has aligned pivot pins 3¹ turnable in bearings in said plates, and a 50 sleeve 56 in which the oar portion 2 bears turnably has aligned pivot pins 4¹ bearing turnably and laterally slidably in the slots 16¹, 17¹ in said plates. Thus the oar may be turned, or "feathered" by the rower about its 55 longitudinal axis.

The invention being intended to be pointed out in the claims, is not to be limited to or by details of construction of any particular embodiment thereof illustrated by the drawings or hereinbefore described.

I claim:

1. In an oar of the character described: a middle member having a slide bearing in fixed relation therewith extending in the oar's longitudinal direction; a blade portion and a

handle portion having their adjacent ends directly connected pivotally, one of said portions being mounted on the middle member swingably, and the other one of said portions being mounted on the middle member swingably and slidably in said bearing. 70

2. In an oar of the character described: a middle member comprising rigidly connected parallel plates having slide bearings elongated in the oar's longitudinal direction; a 75 blade portion and a handle portion between the plates, each of said portions having a pair of bars rigidly secured on its opposite sides by bolts extending therethrough, the adjacent ends of the bars extending inwardly from the 80 adjacent ends of said portions and being swingably connected by a pivot pin passing through said ends of the bars, one of said portions being mounted on the plates by a pivot pin passing therethrough and through the 85 pair of bars secured to said portion, and the other one of said portions being mounted pivotally and slidably on the plates by a pivot pin extending through said bearing and through the pair of bars secured to said second-men- 90 tioned portion.

3. In an oar of the character described for propelling a boat having a spindle extending in the boat's longitudinal direction: a middle member having a slide bearing in fixed relation therewith extending in the oar's longitudinal direction and a rotary bearing removably receiving the spindle turnably therein; a blade portion and a handle portion having 95 their adjacent ends connected pivotally, one 100 of said portions being mounted on the middle member swingably, and the other one of said portions being mounted on the middle mem- 105 ber swingably and slidably in said slide bearing.

4. In an oar of the character described for propelling a boat having a spindle extending in the boat's longitudinal direction: a middle member having a slide bearing in fixed relation therewith extending in the oar's longitudinal direction and a rotary bearing removably receiving the spindle turnably therein; a blade portion and a handle portion having 110 their adjacent ends connected pivotally, one 115 of said portions being mounted on the middle member swingably, and the other one of said portions being mounted on the middle member swingably and slidably in said slide bearing, a releasable catch for holding the 120 middle member on the spindle.

5. In an oar of the character described for propelling a boat having upwardly extending posts spaced in the boat's longitudinal direction and carrying aligned spindles extending in said direction: a middle member hav- 125 ing a slide bearing extending in the oar's longitudinal direction and downwardly ex- 130 tending ears spaced correspondingly with the posts, having aligned rotary bearings removably receiving the spindles respectively turn-

ably therein; a blade portion and a handle portion having their adjacent ends connected pivotally, one of said portions being mounted on the middle member swingably 5 and the other one of said portions being mounted on the middle member swingably and slidably in said slide bearing.

6. In an oar of the character described for propelling a boat having upwardly extending 10 posts spaced in the boat's longitudinal direction and carrying aligned spindles extending in said direction: a middle member having a slide bearing extending in the oar's longitudinal direction and downwardly extending 15 ears spaced correspondingly with the posts, having aligned rotary bearings removably receiving the spindles respectively turnably therein; a blade portion and a handle portion having their adjacent ends connected pivot- 20 ally, one of said portions being mounted on the middle member swingably and the other one of said portions being mounted on the middle member swingably and slidably in said slide bearing, means for releasably hold- 25 ing the middle member on the spindles comprising a catch bar mounted on the middle member and spring-pressed into holding engagement with one of the posts.

7. In an oar of the character described: a 30 middle member having keeper openings; a blade portion and a handle portion pivotally mounted on the middle member and having their adjacent ends connected in swingable interrelation; an element comprising parallel 35 bars removably thrust into the keeper openings in straddling relation with one of said portions for locking said portions against relatively swinging movement; means for mounting the oar on a boat in alternately 40 bow-facing and rear-facing rowing position.

8. In an oar of the character described: a 45 middle member; a blade portion and a handle portion pivotally mounted on the middle member and having their adjacent ends connected in swingable interrelation; releasable means for mounting the middle member on a boat turnably about an axis extending in the boat's longitudinal direction; an element re- 50 leasably locking said portions against relatively swinging movement, said element being removably mounted on the boat turn- ably.

9. In an oar of the character described: 55 a middle member; a blade portion and a handle portion pivotally mounted on the middle member and having their adjacent ends connected in swingable interrelation; releasable means for mounting the middle member on a boat turnably about an axis extend- 60 ing in the boat's longitudinal direction; an element releasably locking said portions against relatively swinging movement, said element being removably mounted on the boat turnably in horizontal and vertical di- 65 rections.

10. In an oar of the character described for propelling a boat having a spindle ex- 70 tends in the boat's longitudinal direction and a vertical bearing: a middle member having on one side a rotary bearing removably receiving the spindle turnably therein, and on the opposite side a keeper opening; a blade portion and a handle portion pivotally mounted on the middle member and having their adjacent ends connected in swingable 75 interrelation; a pivot pin turnable in said vertical bearing; an element turnable on the pivot pin and removably thrust into the keeper opening in engagement with one of said portions for locking said portions against relatively swinging movement, said element being mounted on said pivot pin turnably in horizontal and vertical directions.

11. In an oar of the character described: 80 a middle member; a blade portion and a handle portion mounted on the middle member swingably in a common plane and having their adjacent ends connected in swingable interrelation; an element releasably locking said portions against relatively swinging movement; means for removably mounting the middle member at one side thereof on a boat turnably about an axis extending in the boat's longitudinal direction; means for removably mounting the middle member at 85 the opposite side thereof on a boat turnably in horizontal and vertical directions.

12. In an oar of the character described for propelling a boat having a spindle ex- 90 tends in the boat's longitudinal direction and an axially vertical socket: a middle member having on one side a rotary bearing removably receiving the spindle turnably therein, and on the opposite side a keeper opening; a blade portion and a handle portion pivotally mounted on the middle member and having their adjacent ends connected in swingable interrelation; an element having a part removably inserted into the keeper opening in engagement with one of said portions for locking said portions against relative swinging movement and a part removably inserted in said socket, said parts being connected turnably in horizontal and vertical directions.

In testimony whereof I have hereunto set my hand at Grand Rapids, Michigan, this 19th day of March, 1931.

JOSEPH FRED ROBBIN.
